UNITED STATES PATENT OFFICE

2,477,867

PORTABLE PILE DRIVER

William R. Fairchild, Hattiesburg, Miss.

Original application July 19, 1944, Serial No. 545,690. Divided and this application December 20, 1945, Serial No. 636,159

5 Claims. (Cl. 280—12)

1

The present application is a division of my prior U. S. application, Serial No. 545,690 filed July 19, 1944, upon portable pile driver, now Patent No. 2,423,301, dated July 1, 1947.

The present invention relates to the improved supporting base of the pile driver, which supporting base is in the form of an elongated skid adapted to be drawn along the ground to move the pile driver from one place to another.

The primary object of the invention is to provide a supporting base of the above kind which is comparatively simple and durable in construction, and which may be economically manufactured.

Another object of the invention is to provide a supporting base of the above kind which is especially adapted for use in a pile driver where-in pile driving means is pivoted on one end of the supporting base for folding downwardly onto the latter, and wherein a hoisting truck is adapted to be backed upon the other end of the base in position for actuation of the hoisting cable of the pile driving means, when the pile driving means is swung upwardly to a vertical operative position.

The exact nature of the present invention, as well as more specific objects and features thereof, will become apparent from the following description when considered in connection with the accompanying drawings, in which:

Figure 1 is a fragmentary side elevational view of a pile driver embodying a supporting base constructed in accordance with the present invention.

Figure 2 is an enlarged front elevational view of the construction shown in Figure 1.

Figure 3 is an enlarged rear elevational view thereof.

Figure 4 is an enlarged fragmentary view, partly in elevation and partly in vertical longitudinal section, showing an intermediate portion of the supporting base or skid.

Figure 5 is a fragmentary vertical transverse section taken on line 5—5 of Figure 4, and

Figure 6 is a fragmentary side elevational view showing the forward end portion of the base or skid.

Referring in detail to the drawings, the supporting base is in the form of an elongated skid 5 adapted to be drawn along the ground to move the pile driver from one place to another. The skid comprises a pair of spaced parallel runners 6 which are longitudinally bowed downwardly and trussed or braced in this form by longitudinal trusses 7 providing railings or fences along

opposite sides of the skid. One truss 7 is associated with each runner, and each truss is of the Pratt type with inclined top chords 8, vertical posts 9, and inclined braces 10 extending between said chords and the runners 6 between opposite ends of adjacent vertical posts 9. The chords 8, posts 9 and braces 10 are in the form of pipe sections welded together at the upper ends of the posts and braces, the lower ends of the posts and braces being welded to the associated runner 6. The outer ends of the chords 8 are also welded to the upturned ends 11 of the runners 6.

The runners are in the form of inverted T-irons having transverse bracing webs 12 at suitable regular intervals and between each base or head flange and the vertical flange of the runner. A downwardly and inwardly inclined strip of stiff sheet metal 13 is extended along the inner side of each runner substantially from end to end thereof, and this strip extends across and is welded to the inclined edges of the webs 12 at the inner sides of the runners. The strip 13 is also of a width to extend from the free edge of the inner base flange of the runner to a point adjacent the upper edge of the vertical flange of said runner as shown in Figure 5. In this way, a very rigid and durable runner construction is had. The posts 9 and braces 10 are slotted at 13' at their lower ends to fit over the vertical flange of the runner and to receive the upper edge portion of the strip 13. In this way, the posts and braces are interfitted with the runner and the strip 13 and are welded thereto. The upper ends of the posts 9 and braces 10 are butt-welded to the chords 8.

The runners 6 are rigidly connected in spaced parallel relation by means of transverse or cross-members 14. It will be noted that the front chords 8 are shorter than the rear chords, and the adjacent ends of associated chords are butted and welded together at 15. At this point, there is provided a main vertical post 9a which is larger than the remaining vertical posts 9. An inwardly and downwardly inclined lateral brace 16 is provided between the upper end of each main post 9a and the adjacent transverse or cross-member 14, the upper end of said brace being butt-welded to the adjacent side of the post 9a and having its lower end flattened and bolted to a longitudinal edge of the cross-member 14 as at 17. This effectively braces the trusses against lateral strains, and it will be seen that the particular cross-member 14 to which the braces 16 are bolted preferably includes an

angle iron 18 connecting the runners at the tops of their vertical flanges and welded thereto, a filler plank 19 being fitted in the angle iron 18 and bolted to the latter as at 20.

One of the cross-members 14 is arranged at the front end of the supporting base or skid and includes a plank 21 having an angle iron 22 fitted and bolted upon the forward upper corner thereof. The lower ends of the side rails of an A-frame 23 are pivoted at 24 to the angle iron 22 upon axes transverse to the supporting base or skid. Due to the pivotal mounting at 24, the A-frame 23, together with the parts carried thereby, may be folded rearwardly and downwardly onto the supporting base or skid to facilitate transportation of the pile driver from one place to another when the pile driver is not in use. Suitable means is provided to releasably support the A-frame and parts carried thereby in an upwardly swung operative position perpendicular to the supporting base or skid, which means includes a jointed brace composed of links 26 and 28 and a prop 31, as disclosed in my above mentioned co-pending application.

The A-frame 23 forms part of a pile driving means including a pendulum frame 36 carried by the A-frame 23 and provided with hammer leads or guides 37 for a gravity or drop hammer 38. The hammer 38 is adapted to be raised by conventional means including a hoisting cable (not shown) which is adapted to be extended rearwardly and downwardly from the top of the pendulum frame to the hoisting drum of a suitable portable hoisting truck or vehicle driven onto the rear end of the supporting base or skid.

Planks 59 are laid across and secured to certain of the transverse members 14 of the supporting skid at the rear end of the latter and respectively adjacent the inner sides of the trusses 7 as shown in Figures 1 and 3. Disposed upon and secured to the inner or forward ends of the planks 59 transversely of the skid is a bumper bar 60. The planks 59 form tracks for the hoisting truck, and the bar 60 forms a chock for the rear wheels of said truck when the rear of the latter has been backed into proper position upon the rear end of the base or skid. By making provision for the use of a separate hoisting truck that may be driven off of the skid, the pile driving means may be compactly folded onto the skid even though the latter is no longer than the pile driving means. This eliminates a permanent hoisting mechanism on the base or skid which would otherwise be in the way of the pile driving means when folded, and it also reduces the overall weight of the pile driver proper so that movement of the skid over the ground is made possible with the expenditure of relatively less power.

From the foregoing description, it is believed that the construction and advantages of the present invention will be readily understood and appreciated by those skilled in the art.

What I claim is:

1. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends and directly secured at their lower outer ends to

the ends of the runners, said trusses forming fences along opposite sides of the skid, the space between said trusses being substantially unobstructed from end to end of the skid above said transverse bars.

5 2. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends and directly secured at their lower outer ends to the ends of the runners, said trusses forming fences along opposite sides of the skid, the space between said trusses being substantially unobstructed from end to end of the skid above said transverse bars, and a downwardly and inwardly inclined lateral brace for each truss connecting the latter at the joint between the inner ends of its top chords with one of said transverse bars.

10 3. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends and directly secured at their lower outer ends to the ends of the runners, said trusses forming fences along opposite sides of the skid, the space between said trusses being substantially unobstructed from end to end of the skid above said transverse bars, and a downwardly and inwardly inclined lateral brace for each truss connecting the latter at the joint between the inner ends of its top chords with one of said transverse bars.

15 4. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends and directly secured at their lower outer ends to the ends of the runners, said trusses forming fences along opposite sides of the skid, the space between said trusses being substantially unobstructed from end to end of the skid above said transverse bars, each runner comprising an inverted T-bar provided at intervals and at opposite sides with substantially triangular transverse bracing webs between the intermediate and the head flanges thereof.

20 5. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends and directly secured at their lower outer ends to the ends of the runners, said trusses forming fences along opposite sides of the skid, the space between said trusses being substantially unobstructed from end to end of the skid above said transverse bars, each truss further including vertical posts and inclined tubular form braces extending between the chords and the runner, the lower ends of the posts being slotted to receive the intermediate flange of the runner and being welded to the latter.

25 6. A supporting skid for a pile driver comprising a pair of similar downwardly bowed runners having their end portions similarly gradually inclined to the intermediate portions thereof, transverse bars secured at their ends directly to the runners and rigidly connecting the latter in spaced parallel relation, a truss of the Pratt type holding each runner in its bowed form and including a pair of oppositely inclined straight top chords directly joined at their higher inner ends

and directly secured at their lower outer ends to the ends of the runners, said trusses forming fences along opposite sides of the skid, the space between said trusses being substantially unobstructed from end to end of the skid above said transverse bars, each runner comprising an inverted T-bar provided at intervals and at opposite sides with substantially triangular transverse bracing webs between the intermediate and the head flanges thereof, and a laterally inclined metal strip extending longitudinally of each runner substantially from end to end of the latter and disposed across and welded to the inclined edges of the reinforcing webs at one side of said runner, said metal strips spanning the space between the free edge of one head flange of the runner and the upper edge of the intermediate flange thereof.
